UNITED STATES PATENT OFFICE.

CHARLES L. DAVIDSON, OF NEW YORK, N. Y.

STOKER.

Application filed July 21, 1923. Serial No. 652,879.

This invention relates to stokers.

The object of the invention is to provide means to simplify and improve the construction and operation of stokers to render the same more certain and efficient.

A further object is to provide means which are simple and efficient for drying the fuel and reducing the same to a condition in which it may be ignited at its point of delivery to the stoker grate.

A further object is to provide means for passing heated air from inside the furnace chamber through the fuel in advance of the delivery of the fuel into the furnace chamber, and in the direction of the line of penetration of the ignition of the fuel.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claims.

Referring to the accompanying drawings:

Figure 1 is a broken view in elevation of the front of a furnace showing the application thereto of a fuel drying and heating arrangement in accordance with the principles of my invention.

Fig. 2 is a view in vertical longitudinal section on the line 2—2, Fig. 1, looking in the direction of the arrows.

Fig. 3 is a detached detail view in perspective of a bar employed in the grating or grill of the fuel feed hopper.

The same part is designated by the same reference numeral wherever it occurs throughout the several views.

In the economical operation of stokers it is frequently desirable to employ a cheap grade of fuel, such as anthracite coal of "buckwheat," "rice" or "barley" size, culm, coke braize and other characters of fuel, including bituminous and semi-bituminous coal, lignites and the like. These fuels frequently contain more or less moisture, some of them running as high as 11% or more at times. It is common practice to deliver

the fuel from the furnace feed hopper upon the chain grate, the fuel spreading from the hopper the full width of the grate to the desired thickness of bed. On account of the moisture present in the fuel it has been found difficult, in practice, to effect ignition of the fuel at the point where, or sufficiently

close to the point where the fuel enters the furnace chamber, with the result that there is a failure to effect complete combustion of the fuel in its travel through the furnace, thereby failing to secure the full value and advantage of the fuel in heat production, and a loss of efficiency. Where the conditions of high ratings are desired and variable levels are to be encountered, the loss of efficiency from this cause becomes more pronounced. Various expedients have been proposed to overcome this difficulty. Among these expedients special shapes of fire arches have been devised with the idea of hastening the ignition of the incoming fuel by intensifying the heat directly over the point of entry of the fuel. This, however, is not sufficient and has not proved satisfactory in securing a sufficiently rapid and complete ignition at all times, and with all classes of fuel. Moreover, where particularly small particles of fuel of high moisture content are used the air pressure within the furnace necessary to drive the heat down through the fuel bed at the point where the fuel is finally ignited, creates such an intense heat that it frequently warps or otherwise injures the grates, and sometimes puts the stoker out of commission. Where larger particles of the fuel are used the thorough ignition of the entire lumps is slow, even with the intensified heat caused by a special shape of fire arch, with the result that complete combustion of the fuel is not secured.

Also, in the use of special fire arches the direction of flow of the air supply to the furnace chamber, or through the fuel bed, as well as that of the heated products of combustion, is opposite to the direction of ignition penetration. This retards the process of ignition, frequently the lower layers of the fuel failing to ignite, and where variable loads are required with sudden maximums imposed, the ignition is not only slow, but it frequently fails entirely, and in any event, fuel loss results. It has also been proposed to force heated air through the fuel bed after it has reached and has been spread over the grate surface, but in this case a considerable travel of the fuel through the furnace chamber after entering such chamber takes place before reaching the point where the hot air draft is imposed, or else the fuel is passed from one hopper through a preliminary drying and heating chamber and delivered therefrom into another hopper from which

it is spread onto the traveling chain grate of the furnace. In these cases there is a failure to secure satisfactory results. In the first case noted, ignition of the fuel does not take place at the point where it enters the chamber, and hence there is a retarded ignition, failure to effect complete combustion during the remaining travel of the fuel through the chamber on initial travel of the fuel through the chamber without accomplishing any result, and a loss of efficiency. The second instance noted involves the use of an auxiliary hopper and conveyor which adds to the cost, takes up space, and requires additional care.

It is among the special purposes of my present invention to provide means in a stoker which avoids the difficulties noted, and others, and in a most simple, inexpensive and effective manner, and in carrying out my invention I propose to provide a grating or grill in the front wall of the usual fuel feed hopper which is mounted in the ordinary manner on the front wall of the furnace, and at a point near the lower or delivery end of the said hopper, said grill or grating opening into the lower end of the hopper and also into a closed chamber or wind box to which is connected a pipe or other connection to an air evacuating pump, so as to create a draft from the interior of the furnace chamber through the fuel delivery end opening of the fuel feed hopper and through the body of the fuel in the lower end of the hopper chute. By this means I am enabled to effect the thorough drying of the fuel, and by suitably controlling this draft I am enabled to effect such thorough drying action whatever the character of fuel employed, or whatever may be the degree or percentage of its moisture content. I am also enabled by this simple arrangement to effect at least partial consumption or combustion of smoke in certain cases, where, for instance, fuel of a highly volatile nature is used, by drawing heated smoke, or other unburned products of the combustion from the furnace chamber and passing the same through the incoming fresh fuel, as above explained, as well as by extracting thereby some of the volatiles of the fresh fuel before it enters the furnace chamber, and then returning or passing the same into the furnace chamber beneath the grate where they pass through the fuel bed and are consumed. I also am enabled to effect a preliminary heating of the fresh fuel before it enters the furnace chamber, to a degree sufficient to enable ignition thereof to take place the instant it enters or even just before it enters the furnace chamber, or by the time or before it reaches the grate. Moreover, the direction of travel of the heated air and gases through the fresh fuel is in the direction of ignition penetration, and since the entire

thickness of stream of incoming fresh fuel is traversed by the hot air and gases efficient ignition is attained quickly and its penetration through the entire stream of flow of fuel is effected rapidly and thoroughly. I am therefore enabled to increase the effective length of the grate surface without physical extension thereof, and to secure a more complete combustion of the fuel whatever the size of its lumps, and a very high degree of efficiency is attained even under the most exacting conditions of variable loads and ratings.

In the drawings I have shown a simple illustrative structure embodying the principles of my invention wherein 5 designates the usual fuel feed hopper at the front of a furnace, 6 the usual fire arch, 7 the furnace chamber and 8 the usual traveling or chain grate. These parts may be of the usual or of any desired structure or type, the fuel feed hopper delivering onto the grate at the point where the fuel and grate enter the fuel chamber.

In accordance with my invention I provide the lower portion of the front wall of the hopper, opposite the open delivery end of said hopper, with a grating or grill. This can be constructed in any desired manner. I have shown a simple arrangement wherein the lower portion of the front wall of the hopper is formed of a series of bars 9 which, in the illustrative arrangement shown, are provided with hooked upper ends 10, designed to engage over a supporting rod 11. The lower ends of these bars rest against a rod 12, as shown. Any other suitable arrangement for supporting these bars 9 may be employed. The lower portions of the bars are reduced in width, as indicated at 13, so as to form spaces, openings or passages 14, between the edges of adjacent bars when placed in position for use. In practice these openings or passages 14, should be approximately of the same area as are the openings through the chain grate. The grating or grill portion of the fuel feed hopper is enclosed within a closed chamber 15, with which is connected a pipe 16, through which the chamber 15 may be more or less evacuated of air, thereby creating a draft from the interior of the furnace chamber through the open delivery end of the fuel feed hopper and through the stream of fresh fuel as the same passes down the hopper chute and is spread onto the chain grate which operates therebeneath.

It will be observed that the direction of travel of the heated air and gases from the furnace chamber through the stream of fresh fuel is the same as that of ignition penetration; also that the heated air and gases pass entirely through the stream of fresh fuel and its fuel drying and heating action takes place before the fuel actually reaches

the grate or enters the furnace chamber, and hence the fuel is in condition to become ignited just before or at the time of its entry into furnace chamber, and the penetration of the ignition is rapid and complete throughout the entire thickness of the stream of entering fuel.

5 The heated air and gases drawn through the fuel in the manner above described may 10 be returned into the furnace chamber at some convenient or any desired point beneath the chain grate surface for further utilization, or may be otherwise disposed of, as may be required or desired.

15 It will also be observed that I employ no auxiliary feed hopper or conveyor, as I use only the regular and usual feed hopper which is furnished as a part of the regular equipment. There is nothing added to the 20 length of the chain grate and still I am enabled to effectively utilize the entire chain grate length. I require no additional pre-heating chamber through which the fuel is handled. By controlling the degree of vacuum maintained in the wind box 15, I am 25 enabled to handle any character of fuel employed and am able to take care of any desired range of temperature, or to meet any required variations in load. I am also enabled to effect a substantial reduction of 30 smoke, and to secure a very high degree of fuel economy and furnace efficiency.

It will also be observed that the operation above described does not in any way 35 interfere with the usual draft, forced or otherwise, under which the furnace is operated.

Having now set forth the objects and na-

ture of my invention and a construction embodying the principles thereof, I wish it to 40 be understood that many changes and variations in the details and arrangement may readily occur to persons skilled in the art, and still fall within the spirit and scope of my invention.

45 But what I claim as new and useful, and of my own invention, and desire to secure by Letters Patent is:

1. In a stoker, a furnace chamber, a traveling grate, and a fuel hopper mounted at 50 the front of the furnace chamber and delivering thereinto onto said grate, a supporting rod arranged to extend transversely across the front wall of said hopper, bars supported on said rod and spaced apart at 55 their edges to form spaces therebetween, said bars forming a portion of said front wall opposite the furnace entrance and means to pass hot gases from the chamber through said spaces.

60 2. In a stoker, a furnace chamber, a traveling grate, and a fuel hopper mounted at the front of the furnace chamber and delivering thereinto onto said grate at its point of entry, a supporting rod arranged to extend transversely across the front wall of 65 said hopper, bars supported on said rod and spaced apart at their edges to form a portion of said front wall with spaces therebetween, a closed chamber exteriorly enclosing said bars, and an exhaust pipe connection to said closed chamber.

70 In testimony whereof I have hereunto set my hand on this thirteenth day of July, A. D. 1923.

CHARLES L. DAVIDSON.
